CUSHIONING HOLDER FOR LATHES AND
THE LIKE

William J. Weberg, Chicago, Ill.

Application April 20, 1944, Serial No. 531,869

5 Claims. (Cl. 29—97.5)

This invention relates to improvements in cushioning holders for use in lathes and other rotary cutting machines.

The principal object of the invention is to provide a simple and efficient construction of cushioning devices of the character described, having normally loaded spring means for affording limited endwise yielding movement, together with manually adjustable means for providing additional spring cushioning means at will in accordance with varying requirements.

My invention is adapted for use in lathe centers, either of the live, or rotary type, or of the dead, or non-rotary type, and may also be applied to cushioning tool holders of the type disclosed and claimed in my prior patent, No. 2,327,685, issued August 24, 1943, which are especially adapted to produce limited feeding movement of the tool at the end of a normal feeding stroke of the tool holder.

The invention may best be understood by reference to the accompanying drawings illustrating certain embodiments thereof as applied to lathe centers. In the drawings:

Figure 1 is a longitudinal section of a lathe center holder of the dead or non-rotary type, embodying the principles of my invention.

Figure 2 is a fragmentary front end view of the holder shown in Fig. 1.

Figure 3 is a section taken on line 3—3 of Fig. 1.

Figure 4 is a section taken on line 4—4 of Fig. 1.

Figure 5 is a longitudinal section of a lathe center holder of the live or rotary type, embodying the principles of my invention.

Figure 6 is a section taken on line 6—6 of Figure 5.

Figure 7 is a section taken on line 7—7 of Figure 5.

Figure 8 is a longitudinal section showing a modified form of cushioning holder.

Figure 9 is a front face view of the holder shown in Figure 8.

Referring now to details of the embodiment of my invention illustrated in Figures 1 to 4 inclusive, the holding device consists of a tapered shank 10 adapted to be inserted as usual in the tail stock of a lathe, and a head indicated generally at 11, adapted to receive a lathe center point 12 in non-rotative relation therein. The head 11 has an endwise yieldable holding member 13 therein, consisting of an annular end plate 14 formed integral with a spindle 15 extending into the hollow portion of the shank 10. The end plate 14 has a close sliding fit axially of a cylindrical recess 16 formed in the head 11. A re-

duced end portion 17 of the spindle 15 has sliding engagement in the rear end of the shank 10, so as to maintain the holding member 13 in precise axial alignment within the head 11 and its shank 10 as said holding member slides longitudinally relative thereto. The center point 12 may, as usual, have a tapered fit in the front end of the holding member 13, as shown.

Spring tension adjustment means for controlling the yielding or cushioning movement of the holding member 13 relative to the head 11, includes a plurality of bored recesses 23 and 26 formed adjacent the periphery of the end plate 14 of said holding member, which recesses open inwardly toward the end wall 20 of the hollow head 11, and on axes parallel with the longitudinal axis of the latter. In the form shown, three recesses 23, and an equal number of recesses 26 are shown, disposed alternately on the same diameters, but it will be understood that the number and relationship of these recesses may be varied, if desired.

The recesses 23 each have concentric cap screws 27 extending therethrough from the front face of the end plate 14, in the form shown, the heads 28 of said screws being countersunk in said front face. The threaded inner end portions 29 of the cap screws are engaged in the end wall 20 of the head. A coil spring 31 is mounted on each of said cap screws within its recesses 23, and with its inner end abutting the end wall 20. In practice the coil springs are pre-loaded under a predetermined compression by their respective cap screws 27 so as to tend to urge the end plate 14 away from the end wall 20 of the head 11.

The recesses 26 each have other coil springs 32 therein interposed between the end plate 14 and the end wall 20. A single adjusting device is provided for varying the compression of the springs 32. In the improved form of adjusting means shown herein, each of the coil springs 32 has a plunger 34 associated therewith, said plunger having an outer end 35 inserted through its respective coil spring, and also having an intermediate collar 36 which forms an abutment for the inner end of said spring. The outer end 35 of said plunger is guided for sliding movement in a bore 37 formed in the end plate concentric with its recess 26.

The collars 36 of said plungers 34 are slidably mounted in bored recesses 38, formed in the inner face of the end wall 20. Said plungers also have inner end portions 39, which extend through aligned bores 40, 40 in the end wall 20, and pro-

ject a substantial distance therebeyond, as shown in Figure 1.

The projecting ends 39 of plungers 34 are in position to be simultaneously engaged by a cup-shaped compression control member or cap 41, having an end wall or web 42 normally spaced from the inner end wall 20 of the head 11, and a knurled cylindrical portion 43 threaded on the periphery of the head 11. A plurality of spaced holes 43' may be provided about the knurled portion 43 for the insertion of a suitable spanner wrench or the like, when desired.

The end plate 14 of the holding member 13 is secured in the head 12 by a retaining ring 44, threaded in the front end of the recess 16, with a centrally disposed portion 45 of said end plate extending through said ring, as shown. A felt or fibre washer 46 may surround the central opening of the retaining ring 44 on its inner face, to keep dirt and dust from the interior of the head.

It will now be understood from the foregoing description that the springs 31 are preloaded to a predetermined compression by the cap screws 27 so as to yield only under excessive end thrusts which may be encountered in the kind of operations for which the device is intended to be employed. Thus, when used as a lathe center, the springs 31 may be pre-loaded so the center will not yield under normal free-turning setting of the tail-stock for the lengths and sizes of work usually to be handled, but will yield automatically if such work should become elongated due to heat produced by cutting. In instances where additional spring resistance against yielding movement is desired, an increased amount of such resistance can be readily provided by manual adjustment of the cap 41, which controls the compression of all of the springs 32 simultaneously. It will be noted that this adjustment can be effected without dismounting the device from the lathe, and preferably while mounted on the lathe.

In the form of my invention illustrated in Figures 5 to 7 inclusive, the same principles of a yielding holder under preloaded compression, together with a single manually adjustable device for increasing the effective compression, is shown as applied to a live center for lathes.

In this alternative form of my invention the device consists generally of a hollow head 50 and shank 51 integral therewith, in which is rotatably mounted an end plate 52 with an integral spindle 53 extending into said shank.

The end plate 52 is mounted in suitable anti-friction bearings including a roller bearing member 54 of the needle type disposed within the forward end of the head, and a ball thrust bearing member 55 rearwardly of said roller bearing member. The ball thrust member includes an outer race 56 seated in a rabbeted portion 57 adjacent the inner face of the end plate 52, and an inner race 58 having its outer periphery fitting within the head, in abutting relation with the outer end of a compression spring member 59. The inner end of the spring member 59 engages the end wall 60 of the head. In the form shown herein, the spring member 59 consists of two oppositely-dished discs of spring metal. Said spring member forms part of the auxiliary compression adjusting means, as will presently appear.

The preloaded spring compression, to resist yielding movement of the rotary end plate, is provided by a coil spring 61, mounted in a hollow nut 62 having threaded adjustment in the rear

end of the shank 51. The front end of the spring 61 abuts a ball thrust bearing member 63 which in turn abuts against the rear end of the rotating spindle 53. The arrangement is such, that the front end of the hollow adjusting nut 62 is normally spaced from the ball thrust bearing 63, so as to provide a substantial range of adjustment of the spring compression, but when the nut 62 is screwed home against the said ball thrust member, the cushioning or yielding movement of the holding member 13 is temporarily eliminated.

Forwardly of the thrust bearing member 63 is a roller bearing 64 to rotatably support the rear end of the spindle 53 in the hollow shank 51.

The amount of compression by spring member 59 is adjustable under manual control of the threaded cap 65 on the head 50, through a plurality of plungers 66 having enlarged heads 67 slidably mounted in recesses 68 formed on the inner face of the end wall 60. The heads 67 are adapted to be moved into abutting engagement with the spring member 59 so as to control the degree of the compression of the latter. The rear ends of said plungers 66 extend through said end wall and project a substantial distance therefrom, so as to be simultaneously engaged by the end wall 69 of the adjusting cap 65.

The front end of the end plate is secured in the head 50 by a threaded retaining ring 70 which forms a stop for said end plate.

The rotary type of lathe center holder is especially adapted for use in the tail stock of a lathe, but can also be used in the head stock, if desired.

Among further advantages of the manually adjustable cushioning devices above described is that they can be quickly adjusted while the work is in the lathe to accommodate themselves to variable cutting pressures—especially those which may be temporarily effective in an axial direction toward the cushioning center holder.

Figures 8 and 9 show how the same structural features and principles of operation above described as applied to lathe center holders, can be advantageously applied to cutting tool holders, wherein a cutting tool is suitably mounted on the cushioned end plate in place of the center, so as to constitute a tool holding device of the type disclosed in my Patent No. 2,327,685 hereinabove referred to. In the modified form of device shown in Figures 8 and 9 all of the parts are substantially identical with those shown in the type of holder illustrated in Figures 1 to 4 excepting that the end plate 14 of the holding member 13 is extended to provide a pair of exposed ribs 14a, 14a disposed transversely thereof, having undercut inner faces 15a, 15a forming a slot of the kind shown in my aforesaid prior patent for receiving a cutting tool holder block for slidable adjustment therealong. When so employed, the amount of limited feeding movement of the cutting tool at the end of the normal feeding stroke of the tool holder can be quickly adjusted by manipulation of the single adjusting cap, in accordance with varying needs.

Although I have shown and described certain embodiments of my invention, it will be understood that I do not wish to be limited to the exact constructions shown and described, but that various changes and modifications may be made without departing from the spirit and scope of the invention as defined in the appended claims.

I claim:

1. In a holder of the character described, a

hollow casing member, a tool supporting member mounted for endwise sliding movement in said casing member, a plurality of compression spring devices interposed between said members, said spring devices having independently adjustable means for varying their respective degrees of compression, the adjusting means for one of said spring devices including a plurality of circumferentially spaced, axially-movable plungers extending through an upright wall portion of said casing member, with their forward ends in abutting engagement with their respective spring devices, and a cap-shaped control member threaded on the exterior of said casing member with a flanged portion thereof in operative engagement with said plungers.

2. In a holder of the character described, an enlarged hollow head having a rear wall and an axially disposed shank of reduced diameter extending rearwardly therefrom, a supporting member including an end plate slidably mounted in said head, yieldable cushioning means in said head rearwardly of said end plate, and means for controlling the compression of said cushioning means effective on said end plate, including a cap member having threaded adjustment on the exterior of said head, and a plurality of circumferentially spaced plungers passing through the rear wall of said head with their forward ends operatively connected with said cushioning means and their rear ends operatively engaged by said cap member.

3. In a holder of the character described, an enlarged hollow head having an axially disposed shank of reduced diameter extending rearwardly therefrom, a supporting member including an end plate and a spindle slidably and rotatably mounted in said head and shank respectively, yieldable cushioning means in said head rearwardly of said end plate, and means for controlling the compression of said cushioning means effective on said end plate, adjustable from the exterior of said head, including a cap member threaded on said head, and axially mov-

able abutment means engaging said cushioning means and operatively engaged by said cap member.

4. In a holder of the character described, an enlarged hollow head having an axially disposed shank of reduced diameter extending rearwardly therefrom, a supporting member including an end plate and a spindle slidably and rotatably mounted in said head and shank respectively, 10 yieldable cushioning means in said head rearwardly of said end plate, and means for controlling the compression of said cushioning means effective on said end plate, adjustable from the exterior of said head, including a cap member threaded on said head, and axially movable abutment means engaging said cushioning means and operatively engaged by said cap member, and a second cushioning means adjacent the rear end of said shank, and means for controlling the compression of said second cushioning means effective on said shank including a nut threaded in the end of said shank, and forming a movable abutment for said second cushioning means.

5. In a holder of the character described, an 25 enlarged hollow head, a supporting member telescopically mounted for axial movement in said head, a plurality of springs interposed between said head and supporting member, a plurality of connecting devices maintaining said springs 30 under compression and limiting the relative axial movement between said head and said member, a plurality of other springs interposed between said head and said member, and means for adjusting the compression of said last named spring 35 without affecting the relative movement of said head and member, determined by said connecting devices, said adjusting means including a cap member threaded on the exterior of said head and a plurality of plungers forming abutments 40 for said last named springs, and axially movable through said head for simultaneous operation by said cap member.

WILLIAM J. WEBERG.
